UNITED STATES PATENT OFFICE.

LOTHAR R. ZIFFERER, OF LANCASTER, PENNSYLVANIA.

ADJUSTABLE FLANGE.

Application filed May 11, 1922. Serial No. 560,023.

To all whom it may concern:

Be it known that I, LOTHAR R. ZIFFERER, a citizen of the United States, residing at Lancaster, in the county of Lancaster and State of Pennsylvania, have invented certain new and useful Improvements in Adjustable Flanges, of which the following is a specification.

This invention relates to a flange or plate 10 adapted to be secured adjacent a ceiling or wall from which extends a rod or bolt for supporting purposes; more particularly it has reference to a device adapted for use with pipe hangers such as are used in springer systems, the flange being adjustably secured upon the rod adjacent the ceiling to conceal its point of connection therewith.

An exemplification of my invention in a preferred form is shown in the accompanying drawing wherein—

Figure 1 is a side elevation of a conventional pipe hanger with an adjustable flange operatively positioned thereupon, the same being illustrated in vertical section;

Fig. 2 is a plan view of the flange; and

Fig. 3 is a vertical section therethrough with its parts related as when the flange is being removed from the rod.

In the drawing is shown a ceiling A 30 formed of some such material as concrete wherein is embedded one end of a rod or bolt B which carries an adjustable hanger C formed with a ring D for the suspension of a pipe E. The manner in which the rod 35 is secured to the ceiling is of relative unimportance to this invention, as is also the particular form of hanger that is used therewith.

Associated with a hanger of the kind described is a flange F adjustable lengthwise of the rod to occupy a position adjacent the ceiling for the purpose of concealing the point of its connection therewith. According to my invention this flange comprises 45 a rigid body 5 that is ornamentally configured to provide a hollow circular chamber having an opening 6 through which the rod may freely pass. The upper edges of the body are suitably turned in to embrace the 50 peripheral edges of a circular plate 7 which is thereby assembled permanently with the body. This plate is preferably formed from spring steel and of a gauge that is smaller than the material which is used for the body. In its middle portion this plate is 55 cut out and notched as at 8 in such a man-

ner as to provide a plurality of flexible tongues 9 each of which terminates in a point 10 that is equidistantly situated from the plate center. The pointed ends of these 60 tongues lie in a circular path which is slightly less in diameter than that of the rod B, thereby necessitating a downward flexation of the several tongues when the flange 65 is shoved upwardly against the ceiling, as shown in Fig. 1. The flange so formed will be held in adjusted position lengthwise of the rod through the engagement of the sharp tongue points thereupon, these points 70 tending to bite into the rod whenever any downward pressure is exerted upon the flange. By forming the plate with an odd number of points, all disposed in the same circular path, the flange will automatically 75 be centered upon the rod, and each of the tongue points will engage therewith with a degree of pressure that is substantially 80 equal.

In the installation of pipe hangers such as is shown in Fig. 1, the hanger rods are 80 inserted in the ceiling at or before the time the concrete is poured. Thereafter a flange is adjusted upon each rod to the position shown in Fig. 1. Substantially the same 85 procedure is followed if each rod be secured to the ceiling as through the medium of an expansion bolt or other connecting device. The hanger proper is thereafter applied to the threaded end of the rod and the pipe line 90 suspended thereon in the required position 90 of adjustment.

In case it should be desired to remove any 95 of the present flanges, this may be accomplished by inserting a thin implement between the flange and ceiling and thereafter applying a downward pull sufficient to cause a reversal in the flexing movements of the several spring tongues. As the result of such 100 an operation, the parts will assume a relation such as is shown in Fig. 3, following which the flange may be completely removed from the rod if this be desired. Except when extreme force is used, however, to reverse the 105 positions of the spring tongues, the flange will stay put as shown in Fig. 1, being held firmly against slipping downwardly upon the rod due to the tight impingement of the several tongue points 10.

The construction herein shown and described is one which may be produced and 110 installed economically and expeditiously. Obviously the precise form and method of

manufacture of the flange is of relative unimportance to this invention, the scope of which is to be determined by the claims appended hereto.

5 I claim:

1. In combination with a rod, a flange surrounding the same and comprising two metallic parts, one a rigid body having an aperture through which the rod is extended, and
- 10 the other a spring plate secured to the body and formed to provide a plurality of flexible tongues each adapted for frictional engagement with the rod, the flange being longitudinally adjustable upon the rod, and the
- 15 body co-operating with the plate in its engagement therewith in such a manner as to maintain the flange in transverse relation

thereto in all positions of adjustment thereupon, substantially as described.

2. In combination with a rod, a flange surrounding the same and adjustable longitudinally thereof, the flange comprising two interlocked metallic parts, one rigid and the other flexible, the latter being provided with a plurality of spring elements adapted to 20 frictionally engage with the rod, the rigid part also engaging with the rod and co-operating with the spring elements to maintain the flange in a transverse relation to the rod in all positions of adjustment thereupon, sub- 25 substantially as described.

LOTHAR R. ZIFFERER.
